ELECTRIC SWITCH

William C. Lesher, Pittsfield, Mass., assignor to
 General Electric Company, a corporation of
 New York

Application August 1, 1947, Serial No. 765,369

14 Claims. (Cl. 200—114)

1

My invention relates to improvements in electric switches intended primarily for outdoor installation on distribution systems and more particularly to improvements in disconnecting switches and especially fuse disconnecting switches of the open dropout type.

Fuse disconnecting switches of the open dropout type, with which I am familiar, have been subject to false operations in consequence of animals such as birds, squirrels, etc. getting on the exposed metal parts and causing short circuits. These false operations result in interruptions to the much desired continuity of service. To avoid such interruptions, the terminal portions at the ends of the supporting insulator have been mounted outwardly from the insulator at distances from each other and from the possibly grounded metallic band support which are sufficient to provide the dielectric strike and creepage values required to meet the basic insulation level of the voltage classification for which the switches are designed. However, the voltage classifications of distribution apparatus do not require and it has not been economically practical to provide distances between the terminals and the metallic band support which are sufficient to eliminate the possibilities of animals producing short circuits between the terminals and between the intervening metallic band support of the insulator and either terminal. In addition to being economically impractical, the result of any such expedient to obtain bird-proof distances is a switch of extended structure and ungainly appearance.

In fuse disconnecting switches of the type having an expulsion tube sealed at one end and open at the other end, the expulsion effect of the blowout action tends to move the fuse tube and the parts connected thereto in a direction away from the open end so forcibly as to produce material shock which has to be absorbed and transmitted through the attachment of the parts to the insulator and thence to the insulator mounting. In prior art fuse disconnecting switches of the open type embodying the metallic band support, the effect of this expulsion force has been magnified many times by leverage, since the expulsion tube is mounted at considerable distance from the insulator in order to provide sufficient dielectric-strike distance from the metallic band support to the fuse in the expulsion tube or to the uninsulated solid disconnecting blade it is customary to furnish as an alternative to the fused expulsion tube. These magnified forces result in application to the insulator of stresses

2

such as bending for which the usually employed ceramic structure is ill adapted. In order to meet even current interrupting abilities required on normal distribution circuits without breaking the porcelain insulator or bending the terminals or supporting members so they are no longer usable, it has been proposed to have both ends of the expulsion tube open. However, the expulsion of hot ionized conducting arc gases from the energized end of the tube creates a hazard from arcover to nearby grounded parts or even between associated, electrically energized overhead lines or apparatus terminals. In view of this hazard, various methods have been proposed to limit the range of currents at which expulsion action occurs at both ends or to direct the expelling of the gas away from associated lines or apparatus. Each of these expedients only slightly lessens the hazard. The only positive corrective measure is to seal the end of the expulsion tube which remains energized after the arc is extinguished in the tube since tests have shown that the hot conducting arc gases expelled from the tube can cause flashover to ground members, or those excited at a different potential, even when located from five to six feet from the terminal on the energized end of the expulsion tube whereas no flashover will occur to such grounded or energized members even when located only six inches from the end of the tube which is deenergized by the arc extinguishing action of the tube.

While open type fuse disconnecting switches have been provided with metallic hoods for preventing ice and like formations and keeping rain from the upper contact structure, such hoods have been an integral part of the structure and, in some cases, constitute a part of the latching arrangement. Such hoods not only add materially to the weight and cost of the switch, but inasmuch as they cannot be eliminated without change in structure, they necessitate the manufacture of two lines of switches, one with hoods and the other without, in order to satisfy trade demands. This, of course, adds materially to the cost of the switches.

Fuse disconnecting switches normally are mounted on crossarms at the top of the poles supporting the electric distribution lines. Many times the switch is located out on the end of a crossarm as much as four to five feet from the operator on the pole. It must be operated with a long switch pole in order to reach it and also to prevent the operator from coming in contact with the electrically energized portions of the device, especially of the open type construction.

In swinging the expulsion tube about its hinged support from the open to the closed position the operator frequently exerts considerable sidewise thrust on the free end of the relatively long tube thus making it difficult to assure proper entrance of this free end into the upper latch and terminal on the insulating support. Widely extending guiding arms have been used on the upper latch and terminal but these do not permit ready provision of a hood to cover and protect the upper terminal.

It has been proposed to have disk-like bearing or guiding surfaces on the hook and trunnions of the hinge for the expulsion tube so as to guide the free end into a hooded upper latch and terminal. However, the necessary very close machining limits on the guiding surfaces proved too costly for a class of apparatus of which so many units are required in order adequately to protect an electric distribution circuit.

An object of my invention is to provide an improved electric switch structure, particularly of the open fuse type, such that the possibility of short circuits and false operations in consequence of birds and other wild life getting across the exposed energized metal parts of the switch is so materially reduced as to be practically eliminated. Another object of my invention is to provide an improved electric switch structure, especially of the open fuse type, with the insulator supporting member so secured to the insulator as to permit positioning the expulsion tube in such a way that the stresses on the support caused by the expulsion or blowout effect are not magnified by extended supporting arms or terminals. Also an object of my invention is to provide an improved electric switch structure, particularly of the open type, which is compact, sturdy, and of pleasing appearance. Still another object of my invention is to provide an improved expulsion fuse disconnecting switch of the open type wherein the expulsion force accompanying the ruptures of the fuse is absorbed and transmitted to the supporting insulator in such a manner as to minimize the effect of the shock. A further object of my invention is to provide for the contact structure of a disconnecting switch a readily and simply attachable and detachable hood of insulation which is light and economical. A still further object of my invention is to provide an improved disconnecting switch of the hook bearing type such that lateral deviation, particularly during a closing movement of the movable conducting member, is practically eliminated. These and other objects of my invention will appear in more detail hereinafter.

My invention will be better understood from the following description when considered in connection with the accompanying two sheets of drawings, and its scope will be pointed out in the appended claims.

In the accompanying drawing, Fig. 1 is a side elevation of a fused disconnecting switch of the open dropout type embodying my invention and shown in the circuit closed position; Fig. 2 is an enlarged view similar to Fig. 1 with some parts broken away for clearness of illustration and in addition showing in broken lines some intermediate positions of the movable parts; Fig. 3 is a front elevation of the switch shown in Fig. 2 with the switch shown in the full open position; Fig. 4 is a view similar to Fig. 1 illustrating the switch with the parts in position just prior to dropout and also showing in broken lines the fuse

tube in an intermediate position following the blowout of the fuse and in its extreme open position; Fig. 5 is an enlarged sectional view taken on the line 5—5 of Fig. 2 illustrating the upper switch terminal structure and its mounting; and Fig. 6 illustrates a modification of my invention wherein the switch is purely a disconnecting switch without a fuse and without dropout action.

For the purpose of illustrating my invention, I have shown in Figs. 1 to 4, inclusive, a fuse disconnecting switch of the open dropout type wherein the line terminals 1 and 2 and associated contact structures are mounted adjacent the ends of a suitable substantially cylindrical insulator 3. In order to have a compact structural arrangement whereby to avoid multiplying the expulsion recoil forces as they stress the porcelain and supporting member and also to avoid false operations in consequence of short circuits produced when birds and other wild life contact conducting parts of a switch, such as the terminals, for example, the insulator supporting arm 4 is mounted so a portion near one end thereof is within the cylindrical surface of the insulator 3 at the rear thereof and approximately midway of the ends of the insulator. With the supporting arm 4 thus extending directly from the insulator in a direction opposite to the contact structure hereinafter described, a more effective strike-over distance to the fuse 19 in tube 21 or to the metallic tube 62 shown in Fig. 6, when substituted for the tube 21, is insured even with the tubes 21 or 62 located closer to the insulator 3 than has been possible with the heretofore used metallic band support around the outside of the middle portion of the insulator. Thus, in my construction, I combine mounting of the support 4 in the insulator 3 at the rear thereof and the location of the tube 21 or 62 closer to the insulator 3. This provides a more economical construction for open type switches and insures not only an interrupting ability comparable with that of switches of the enclosed type but also, with minor modifications of the expulsion tube 21 and associated parts comprising current conducting means 18, a device with an interrupting ability nearly double that of the normal interrupting ability and with the end of the tube 21, which is normally energized after arc extinguishing, sealed by the cap 22 so as to prevent strike-over to associated lines of apparatus. As illustrated in Figs. 1 and 2, arm 4 is secured to a support such as a pole-mounted bracket 5 by suitable fastening means shown as a bolt 6 provided with a nut 7, a bearing washer 8 and a lock-washer 9.

Adjacent one end of the insulator 3 and supported therefrom in conductive relation with the terminal 1 and so as to extend transversely of the insulator in a direction oppositely to that of the support 4 is a first relatively stationary contact means 10. Inasmuch as the tube 21 can be located closer to insulator 3, as hereinbefore described, the stationary contact means 10 is relatively shorter than heretofore possible in devices of the prior art thus decreasing the leverage which multiplies the recoil forces from expulsion action. Supported from the other or lower end of the insulator 3, in line with the longitudinal axis thereof is a hinge means comprising a hook type bearing member 11, the bearing axis 12 of which is substantially perpendicular to the longitudinal axis of the insulator and displaced from the insulator axis oppositely to the dis-

placement of the contact means 10. At the other or lower end of the insulator 3, there is mounted on the bearing member 11 a second relatively stationary contact means 13 in current conducting relationship with the terminal 2. For completing a conducting path between the stationary contact means 10 and 13 and consequently the terminals 1 and 2, I provide a hinge element 14 having trunnions 15 adapted to be inserted in the hooks 16 of the bearing element 11 and carrying a contact 17 movable into and out of engagement with the lower contact means 13 upon rotation of the hinge element. Also, I provide current conducting means indicated generally by 18 and carried by the hinge element 14 and rotatable therewith counterclockwise, as viewed in the drawings, about its bearing axis 12 to the circuit closed position to establish the conducting path between the lower and upper contact means 10 and 13.

As shown in Figs. 1 to 4, inclusive, the current conducting means is of the expulsion fuse type comprising a conductor 19 having a portion 20 fusible at a predetermined value of current and an expulsion tube 21 having a conducting cap 22 connected to one end of the conductor and engageable with the upper stationary contact means 10. The fusible portion 20 of the conductor 19 is mounted within a cylindrical casing 23 of insulating material and is connected to the cap 22 through a stud 24 which carries the casing 23 and a button head, not shown, engageable by the cap 22, as is well known to the art, when sealing the fuse tube 21 is practical in the light of the required interrupting duty. As shown, the tube 21 is pivotally mounted at 26 on the hinge element 14 constituting therewith a toggle which is held in the rigid condition shown in Figs. 1 and 2 by tightening the conductor 19 around a thumb screw 27 in the hinge element 14 and then clamping the conductor between the element and a locked-against-turning nut 28. When the toggle is thus held rigid, the switch can be closed by inserting a switch hook in an operating eye member 29 mounted on the fuse tube 21.

For maintaining the switch in the closed circuit position after turning the rigid toggle counterclockwise, as viewed in the drawings, to the closed circuit position shown in Figs. 1 and 2, there is provided a holding means which, as illustrated, comprises a U-shaped resilient member 30, the outer ends of the legs of which are bent inwardly and then outwardly to provide, in V-shaped formation, flared ends which yield sufficiently to permit entrance of the cap 22 and thereupon close over the cap to prevent reverse movement except when enough pull is exerted on the eye member 29 to expand the legs of the U-shaped member 30 sufficiently for exit of the cap.

In order to reduce static interference of radio equipments and the like, a coiled spring-like conductor 31 is placed around the fuse tube 21 between the eye member 29 and the bottom of a threaded sleeve 31' onto which the cap 22 is threaded whereby to have the eye member at the same potential as the terminal 1.

Referring now more particularly to other features of the heretofore described structure, the upper stationary contact means comprises in addition to the leaf contact spring 10 a leaf backing spring 10'. Both of these springs, as shown more clearly in Fig. 2, are carried by a bracket 32 extending outwardly from the insulator 3 and supported therefrom on a stud 33 mounted in the

insulator. For simplicity in mounting, the contact structure 10, 10' is secured to the bracket 32 by the terminal bolt 1 which is provided with a shouldered cylindrical nut 34 having a ridged periphery. The smaller diameter portion of the nut 34 fits into a hole in the spring member 10' and clamps the spring contact 10 against the bracket 32, as shown in both Figs. 2 and 5, thereby establishing electrical contact with the spring contact 10. The inner end of the spring 10 is notched and curved upwardly to engage the stud 33 whereby to prevent turning movement. The inner end of the backing spring 10' bears on the curved portion of the contact spring 10, and the smaller diameter portion of the nut 34 is somewhat longer than the thickness of the backing spring 10' so as to provide greater freedom of movement of the backing spring. Also, the front end of the bracket is bent downwardly so that the contact spring 10 can follow the cap 22 during the first part of the dropout action of the switch, as shown in Fig. 4, whereby to maintain continuity of contact until the expulsion action of the fuse and arc interruption in the tube 21 have occurred. The extreme end of the bracket 32 is further curved downwardly at 35 to provide a support for the U-shaped holding member 30, the base of which is secured to the bracket by suitable means such as a bolt 36 provided with a shock-absorbing head 37 of suitable resilient material to absorb the closing impact. As the switch opens during the dropdown action of the fuse tube, particularly under small currents which effect slow melting of the fuse and weak expulsion action, the cap 22 remains in conducting engagement with the holding member 30. This provides some delay without circuit interruption at the top whereby to insure arc clearing in the tube 21.

The fuse tube 21 is supported in a clamp 38 which is pivotally secured to the hinge element 14 at 26. For lateral stability relatively to this element, the lower end of the tube 21 is held between side arms 39 on the element. In order that the toggle comprising the hinge element 14 and the tube 21 may, when held rigid, swing in substantially a true plane and thus align the cap 22 with a relatively narrow entrance of the holding member 30 so as to be suitable for covering with a hood 52, the hinge element is provided with bearing shoulders 40 which ride against the inside surfaces of the hooks 16 and from which the trunnions 15 protrude outwardly since this structure is mechanically simple to machine. Also, in order to increase the manufacturing limits for this simple machine operation and for the hooks 16 to those of normal low cost manufacture, the bearing member 11 is provided with flared wing guides 41 with which cooperates a relatively close fitting flange 42 on a supporting leg 43 of the hinge element. The relatively large distances between the trunnions 15 and between the guides 41 makes a more positive guide for directing the cap 22 into the relatively narrow entrance of the holding member 30 than has been achieved in prior art constructions with which I am familiar. To limit the angular movement of the tube 21 relatively to the hinge element 14 during the dropout action, the upper end of the supporting leg 43 is provided with an extension 44 which bears against a clamping screw 38' after a predetermined amount of dropout movement has occurred. The hinge element 14 is also provided with an eye member 45 by which the element and the tube 21 can be removed when in the open or

vertically down position for inspection, fuse replacement, etc. with the aid of the usual switch hook.

As shown, the lower stationary leaf spring contact 13 is supported on a bracket 46 which is suitably secured to the outside of the rear wall 47 of the bearing member 11. For holding the contact on the bracket 46, the terminal bolt 2 extends through the outstanding leg of the bracket and is provided with a cylindrical clamping nut 48 which has a ridged periphery and which bears against the contact 13. In accordance with my invention, the contact 13 extends through an opening in the rear wall of the bearing member 11 so as to be engaged by the contact 17 on the hinge element 14 when the switch is closed. Also in accordance with my invention, the bearing member 11 is supported on a stud 49 extending axially downward from the lower end of the insulator 3 substantially in line with the axis thereof and also substantially in line with the point of engagement of the contacts 13 and 17. Further in accordance with my invention, I provide shock-absorbing means positioned adjacent the lower end of the insulator and yieldable substantially in the direction of the axis of the insulator for absorbing the effect of the expulsion force transmitted to the hinge element 14 and thence through stud 49 and insulator 3 to supporting arm 4 so the insulator 3 is essentially in compression substantially along the axis thereof upon rupture of the conductor 19 as at the fusible portion 20 thereof. As illustrated, this means comprises a helical compression spring 50 which is positioned around a reduced diameter portion 51 of the stud 49 and between the inside of the upper wall of the bearing member 11 and the upper surface of the contact 13.

Also a resilient bumper 50', of rubber or the like, is inserted inside the spring 50 and arranged so as to be compressed between the stud 51 and the upper surface of the contact 13 after the spring 50 has been compressed a predetermined amount. Additionally in accordance with my invention, the length of the reduced portion of the stud 49 and the resilient bumper 50' is such that, even though the hinge element is forcibly lifted by the expulsion shock, the contact 13 will strike and compress the bumper 50' a predetermined amount against the end of the stud 49 so as to cushion the impact and stop the upward movement before the trunnions 15 are raised far enough to be movable out of the hooks 16, and also before the upward movement of the tube 21 under the action of the recoil forces has overstressed the terminal 1 and acting through said terminal has imposed a slightly amplified bending stress on the insulator 3.

Again in accordance with my invention, since the bearing axis 12 of the hinge element 14 is to the left of the axis of the insulator 3, the line of action of the force exerted on the hinge element by the compression spring 50 through the contact spring 13 and the contact 17 is such that this force tends to maintain a high contact pressure between the contacts 13 and 17. Also, because of the direction of application of this force, it tends to move the hinge element 14 to the circuit open position whereby to accelerate the opening action when the conductor 19 is ruptured. Also, in order to protect the parts associated with the terminal 2 from the elements, the bearing member 11 is preferably in the form of a hood with only the front and lower sides open. In

order to limit the angular opening movement of the hinge element under the expulsion action, the rear wall 47 of the bearing member 11 extends downwardly into the path of movement of the eye portion 45 of the hinge element, as more clearly indicated by the broken line position X in Fig. 4.

For sheltering the upper contact structure against the elements and also to make this contact structure practically inaccessible to wild life, I provide, in accordance with my invention, an improved hood structure which is readily and simply attachable to and detachable from the switch. As shown, this structure comprises a hood 52 preferably of insulating material which may be formed by molding or otherwise. For ease in mounting, the bottom of the hood is open and also the front in order to allow passage of the cap 22 to and from the circuit closed position. Also for simplicity in mounting, the rear wall of the hood 52 is notched at 53 to fit over the stud 33 between the insulator 3 and the fixed end of the bracket 32, and the top wall 54 is provided with an opening just large enough to slip over and register with the periphery of the cylindrically headed nut 34 on the terminal bolt 1. In order to prevent turning of the hood 52 about the head of the nut 34 the interior of the hood is arranged to engage the bracket 32. For clamping the hood in place and also keeping water from entering the hood, I provide a clamping nut 55 and a cupped spring washer 56, as shown more clearly in Figs. 1 and 5. In order to avoid bending strains on the top wall of the hood 52 under the clamping action, the inside of the top wall is provided adjacent the hole in the wall with transversely extending thick bearing portions 57 which seat on the bracket 32, as shown most clearly in Fig. 5. These portions take in compression the clamping force consequent on tightening the nut 55. Also the hood 52 may be provided with internal stiffening ribs 58, as shown. For securing line conductors to the terminals 1 and 2, each is provided with a wire clamp 59, a lock washer 60 and a nut 61, as shown.

From the foregoing, it will be apparent that in consequence of having the supporting arm 4 extend outwardly from the insulator oppositely to the contact structure without the use of a band surrounding the middle of the insulator, it is possible to bring the contact structure in closer to the insulator without danger of wild life effecting short circuits between the contact structure and the supporting arm 4, which is often grounded. Also, because of the compact structure, less room is available for perching birds and the like to alight on the switch and have any material freedom of movement without having to take off. This practically eliminates the possibility of two birds alighting on the switch at the same time and fighting with each other with resultant possibility of a short circuit across the line. Likewise, the probability of a bird being able to perch on the contact structure and reach around to the supporting arm 4 is greatly minimized. Also, with the contact structure closer into the insulator, the construction is materially stronger and less stress is placed on the insulator due to the decrease in the lever arms. Also, the compactness of structure provides a more pleasing appearance which is further enhanced by the use of the protecting hood 52.

It will be observed that the expulsion type circuit interrupter, comprising the tube 21 and the conductor 19, in the closed position bridges the

upper and lower stationary contacts 10 and 13 in a direction forming a relatively small acute angle within a range of 10 to 30 degrees with the longitudinal axis of the insulator 3. The expulsion force on interruption is thus applied to the top and bottom of the insulator 3 through relatively long and short lever arms, respectively. But since this expulsion force is largely absorbed by the spring 50 and the bumper 50' and the upper travel is limited by the bumper 50' and the stop 51, very little of the force is left to produce bending stresses at the top of the insulator 3 and the effect of this little is eased by the resilient action of the spring contact means 10, 10'.

Assuming the switch in the circuit closed position, as shown in Figs. 1 and 2, with the toggle comprising the tube 21 and the hinge element 14 held in the rigid condition against the bias of the contact springs, the helical spring 50 and gravity by the conductor 19, then if sufficient current flows through the switch to melt the fusible portion 20 of this conductor, the toggle is free to collapse under its bias as soon as the fuse parts. When this occurs, the parts assume the full line condition shown in Fig. 4 with the fuse tube initially being urged downwardly by the resilient action of the contact means 10, 10' and 13 and the helical spring 50. The cap 22 at the upper end of the fuse tube, however, rides downwardly inside of the holding means 30 until the conductor 19 is blown from the fuse tube 21 whereupon the tube assumes the position Y shown in broken lines in Fig. 4 and also in Fig. 2. Under the force of gravity and the biasing impulse initially imparted to the tube, the hinge element 14 and the parts associated therewith move in a clockwise direction until the eye 45 of the hinge element contacts the rear wall 47 of the bearing member, as indicated by the broken line position X in Fig. 4 and then finally swing back to a vertical position below the insulator under the effect of gravity.

When it is desired to re-fuse the switch, the hinge element 14 is lifted out of the bearing member 11 by using a switch hook or the like in the eye 45. A new fusible element is inserted in the tube 21 after first removing the cap 22 and then restoring it to lock the fuse head at the top of the tube as is well known to the art. The new fused conductor 19 is then inserted around the clamping bolt 27 and this bolt tightened to lock the fuse so as to hold the toggle rigid. The tube with a new fused conductor 19 in the toggle retaining position is shown in broken lines in Fig. 2 in the position Z just after restoring the hinge element 14 in the bearing member 11. The switch may then be closed by inserting a switch hook in the eye 29 and moving the rigid toggle about the bearing axis 12 into the position shown in full lines in Fig. 2 where the switch is maintained by the holding means 30 as long as the toggle is held rigid.

The embodiment of my invention shown in Fig. 6 is an adaptation of the fuse dropout switch shown in Figs. 1 to 5, inclusive, for use as a disconnecting switch nonresponsive to current conditions or for use as a non-dropout type of fuse disconnecting switch by fastening the fuse tube 21 to the hinge element 14 by a screw 63 as shown in Fig. 6. In the case of a disconnecting switch, as shown in Fig. 6, the fuse tube 21 is replaced by a tubular conducting member 62 which is attached to the hinge element 14 in a manner similar to the arrangement shown in the

other figures except that, since no relative movement is to take place between the hinge element and the conducting tube 62, the lower end of the tube is also secured to the hinge element to prevent movement about the pivot 26. For this purpose, any suitable means such as a screw 63 projecting through the tube 61 and threaded into the hinge element may be used. To prevent any twisting action of the tube 62, the tube 10 may be notched at 64 so as to seat one of the clamping bolts, not shown, of the clamping means 38. In this modification of my invention, of course, both the circuit opening and circuit closing movements are to be performed manually by 16 means of a switch hook slipped in the eye, not shown, on the tubular member 62.

While I have shown and described my invention in considerable detail, I do not desire to be limited to the exact arrangements shown, but 20 seek to cover in the appended claims all those modifications that fall within the true spirit and scope of my invention.

What I claim as new and desire to secure by Letters Patent of the United States is:

25 1. An electric switch comprising an insulator, a first contact means supported on said insulator adjacent one end thereof, a hook type bearing member supported from the other end of the insulator, a second contact means supported adjacent the other end of the insulator, a hinge element provided with trunnions adapted to be inserted in the hooks of said bearing member, said hinge element having a portion spaced from said other end of said insulator and in line with the longitudinal axis thereof, a contact on said hinge element cooperating with said second contact means, current conducting means carried by said hinge element and rotatable therewith in one direction to the circuit closed position to establish a conducting path between said two contact means comprising an expulsion tube mounted on said hinge element and having a contact cap engageable with said first contact means, a conductor mounted in said tube to extend between said cap and said element and provided with a fusible portion and means for clamping said conductor to said element, and shock-absorbing means including a resilient member positioned between said axially aligned portion of said hinge element and said other end of the insulator and yieldable substantially in the direction of the axis of the insulator for absorbing the effect of the expulsion force transmitted to the hinge element upon rupture 55 of said conductor.

2. An electric switch comprising an insulator, a first contact means supported on said insulator adjacent one end thereof, a hook type bearing member supported from the other end of the insulator, a second contact means supported adjacent the other end of the insulator, a hinge element provided with trunnions adapted to be inserted in the hooks of said bearing member, said hinge element having a portion spaced from said other end of said insulator and in line with the longitudinal axis thereof, a contact on said hinge element cooperating with said second contact means, current conducting means carried by said hinge element and rotatable therewith in one direction to the circuit closed position to establish a conducting path between said two contact means comprising an expulsion tube mounted on said hinge element and having a contact cap engageable with said first contact means, a conductor mounted in said tube to extend be-

tween said cap and said element and provided with a fusible portion and means for clamping said conductor to said element, and means for absorbing the effect of the expulsion force transmitted to the hinge element and limiting the upward movement thereof upon rupture of said conductor comprising a stud centrally mounted in said insulator at said other end thereof in line with the path of upward movement of the contact on said hinge element and a helical compression spring around said stud between the insulator and said axially aligned portion of said hinge element.

3. An electric switch comprising an insulator, a first contact means supported on said insulator adjacent one end thereof, a hook type bearing member supported from the other end of the insulator, a second contact means supported adjacent the other end of the insulator, a hinge element provided with trunnions adapted to be inserted in the hooks of said bearing member, said hinge element having a portion spaced from said other end of said insulator and in line with the longitudinal axis thereof, a contact on said hinge element cooperating with said second contact means, current conducting means carried by said hinge element and rotatable therewith in one direction to the circuit closed position to establish a conducting path between said two contact means comprising an expulsion tube pivotally mounted on said hinge element and having a contact cap engageable with said first contact means, a conductor mounted in said tube to extend between said cap and said element and provided with a fusible portion and means for clamping said conductor to said element to hold the element and the tube against relative movement until rupture of the conductor, and means for absorbing effect of the expulsion force transmitted to the hinge element upon rupture of said conductor comprising a helical compression spring mounted between said axially aligned portion of said hinge element and said other end of the insulator with its axis substantially in line with the axis of the insulator.

4. In a fuse disconnecting switch of the open dropout type, an insulator, a first contact means supported on said insulator adjacent one end thereof, a hook type bearing member supported from the other end of the insulator in line with the longitudinal axis thereof, a second contact means supported on said bearing member, toggle means for establishing a conducting connection between said two contact means comprising a hinge element having trunnions insertable in the hooks of said bearing member and carrying a contact engageable with said second contact means and an expulsion fuse tube pivotally associated with said element and carrying at its free end a contact cap adapted to cooperate with said first contact means, said contact carried by said hinge element being spaced from said other end of said insulator and in line with the longitudinal axis thereof, means for holding said toggle rigid comprising a conductor in said tube extending from said cap to said element and secured thereto, said conductor having a fusible portion, means for maintaining said toggle while rigid with said contact cap in engagement with said first contact means and the contact on said element in engagement with said second contact means, and a resilient member interposed between said contact carried by said hinge element and said other end of the insulator and yieldable substantially in the direction of the axis

thereof for absorbing the expulsion force transmitted to the hinge element upon rupture of said conductor.

5. An electric switch comprising an insulator, a first relatively stationary contact means supported on said insulator adjacent one end thereof to extend transversely from the insulator, a hook type bearing member supported from the other end of the insulator in line with the longitudinal axis thereof with its bearing axis substantially perpendicular to the longitudinal axis of the insulator and displaced from said axis oppositely to the displacement of the first stationary contact means, a second relatively stationary contact means mounted on said bearing member, a hinge element provided with trunnions adapted to be inserted in the hooks of said bearing member, a contact on said hinge element movable therewith into and out of engagement with said second relatively stationary contact means upon rotation of said hinge element, said contact on said hinge element being spaced from said other end of said insulator and in line with the longitudinal axis thereof, current conducting means carried by said hinge element and rotatable therewith in one direction to the circuit closed position to establish a conducting path between said two stationary contact means comprising an expulsion tube pivotally mounted on said hinge element and having a contact cap engageable with said first stationary contact means, a conductor mounted in said tube to extend between said cap and said element and provided with a fusible portion and means for clamping said conductor to said element to hold the element and the tube against relative movement until rupture of the conductor, resilient means positioned between said other end of the insulator and said second contact and hinge element contact engageable therewith to exert on said second contact means a force substantially in line with the axis of the insulator whereby to maintain a relatively high contact pressure between the second stationary contact means and the contact on the hinge element and whereby to tend to rotate the element in the circuit opening direction of said conducting means and to absorb the effect of the expulsion force transmitted to the hinge element upon rupture of said conductor, and means adjacent said first stationary contact means for maintaining said current conducting means and said hinge element in the circuit closed position.

6. An electric switch comprising an insulator, a first relatively stationary contact means supported on said insulator adjacent one end thereof to extend transversely from the insulator, a hook type bearing member supported from the other end of the insulator in line with the longitudinal axis thereof with its bearing axis substantially perpendicular to the longitudinal axis of the insulator and displaced from said axis oppositely to the displacement of the first stationary contact means, a second relatively stationary contact means mounted on said bearing member, a hinge element provided with trunnions adapted to be inserted in the hooks of said bearing member, a contact on said hinge element movable therewith into and out of engagement with said second relatively stationary contact means upon rotation of said hinge element, said contact on said hinge element being spaced from said other end of said insulator and in line with the longitudinal axis thereof, current conducting means

carried by said hinge element and rotatable therewith in one direction to the circuit closed position to establish a conducting path between said two stationary contact means, resilient means positioned between said other end of the insulator and said second contact and hinge element contact engageable therewith to exert on said second contact means a force substantially in line with the axis of the insulator whereby to maintain a relatively high contact pressure between the second stationary contact means and the contact on the hinge element and whereby to tend to rotate the element in the circuit opening direction of said conducting means, and means adjacent said first stationary contact means for maintaining said current conducting means and said hinge element in the circuit closed position.

7. An electric switch comprising an insulator, a first relatively stationary contact means supported on said insulator adjacent one end thereof to extend transversely from the insulator, a hook type bearing member supported from the other end of the insulator in line with the longitudinal axis thereof with its bearing axis substantially perpendicular to the longitudinal axis of the insulator and displaced from said axis oppositely to the displacement of the first stationary contact means, a second relatively stationary contact means mounted on said bearing member, a hinge element provided with trunnions adapted to be inserted in the hooks of said bearing member, a contact on said hinge element movable therewith into and out of engagement with said second relatively stationary contact means upon rotation of said hinge element, said contact on said hinge element being spaced from said other end of said insulator and in line with the longitudinal axis thereof, current conducting means carried by said hinge element and rotatable therewith in one direction to the circuit closed position to establish a conducting path between said two stationary contact means comprising an expulsion tube pivotally mounted on said hinge element and having a contact cap engageable with said first stationary contact means, a conductor mounted in said tube to extend between said cap and said element and provided with a fusible portion and means for clamping said conductor to said element to hold the element and the tube against relative movement until rupture of the conductor, and a helical compression spring positioned between said other end of the insulator and said second contact and hinge element contact engageable therewith to exert on said second contact means a force substantially in line with the axis of the insulator whereby to absorb the effect of the expulsion force transmitted to the hinge element upon rupture of said conductor.

8. In a fuse disconnecting switch of the open type, a supporting insulator, a bracket projecting from said insulator adjacent one end thereof and extending transversely of the insulator, stationary contact means supported on said bracket, movable contact means engageable with said stationary contact means, a terminal bolt and nut for securing said contact means to said bracket, means for sheltering the top and sides of said contact means comprising a hood having its top wall provided with an opening registerable with the periphery of the nut on said terminal bolt, fastening means engageable with said terminal bolt to maintain said hood firmly in position on said bracket and separate latching means independent of said hood secured to said bracket for main-

taining said stationary and movable contact means in engagement.

9. In a fuse disconnecting switch of the open type, a supporting insulator, a stud projecting from said insulator adjacent one end thereof and extending transversely of the insulator, a contact terminal bracket secured to said stud and extending transversely of the insulator, leaf spring contact means fixedly mounted on said bracket and provided with a notched portion in engagement with said stud, a terminal bolt and nut for securing said contact means to said bracket, movable contact means engageable with said fixedly mounted contact means, a hood of insulating material having its top wall provided with an opening just large enough to register with the periphery of the nut on said terminal bolt, and fastening means engageable with said terminal bolt to hold said hood firmly in position on said bracket and separate latching means independent of said hood for maintaining said fixedly mounted and movable contact means in engagement.

10. In a fuse disconnecting switch of the open type, an insulator, a stud projecting from said insulator adjacent one end thereof and extending transversely of the insulator, a contact terminal bracket secured to said stud and extending transversely of the insulator, leaf spring contact means, a terminal bolt and nut for securing said contact means to said bracket, contact means mounted on said insulator near the other end thereof, fused conducting means pivotally associated with the insulator adjacent said other end thereof and movable into engagement with said leaf spring contact means to complete a conducting path therefrom to the contact means mounted on the other end of the insulator, a hood of insulating material having a notched rear wall adapted to be slipped over said stud between the insulator and the fixed end of the bracket and having its top wall provided with an opening just large enough to register with the periphery of the nut on said terminal bolt, fastening means engageable with said terminal bolt to hold said hood in place on said bracket, said hood having front and bottom openings to permit the angular movement of said conducting means into engagement with said leaf spring contact means and the dropout of said fused conducting means upon rupture thereof and separate latching means independent of said hood secured to said bracket for maintaining said conducting means in the circuit closed position.

11. An electric circuit interrupter comprising an insulator, a first contact means mounted on said insulator adjacent one end thereof and extending transversely of the insulator, a second contact means mounted on the other end of said insulator, holding means having relatively narrow flaring arms associated in compact arrangement with said first contact means, a hook type bearing member supported from the other end of said insulator and associated with said second contact means, said bearing member having flaring arms, a hinge element provided with trunnions adapted to be inserted in the hooks of said bearing member, said hinge element having a flange portion extending transversely with respect to said flaring arms and movable in guiding relation between and engageable with said arms of said bearing member, and circuit interrupting means mounted on said hinge element for pivotal movement into and out of bridging position with said contact means.

12. An electric circuit interrupting device com-

prising an insulating support, a first contact means mounted on said support adjacent one end thereof, a second contact means mounted on the other end of said support, hinge means associated with said second contact means, said hinge means having a portion spaced from said other end of said insulating support and in line with the longitudinal axis thereof, a circuit interrupter mounted on said hinge means for pivotal movement into and out of a bridging position for electrically interconnecting said contact means, said interrupter exerting a force on said hinge means during circuit interruption, and a member interposed between said axially aligned portion of said hinge means and said other end of said support for absorbing said force and transmitting it to said insulating support substantially in compression thereon along the axis of the support.

13. An electric circuit interrupting device comprising an insulating support, a first contact means mounted on said support adjacent one end thereof and extending transversely of the support, a second contact means mounted on the other end of said insulating support, hinge means associated with said second contact means, said hinge means having a portion spaced from said other end of said support and in line with the longitudinal axis thereof, a circuit interrupter mounted on said hinge means for pivotal movement into and out of a bridging position for electrically interconnecting said contact means, said interrupter exerting a force on said hinge means during circuit interruption in a direction away from the hinge means and toward said first contact means, a shock-absorbing member interposed between said axially aligned portion of said hinge means and said other end of said support for absorbing said force and transmitting it to said insulating support substantially in line with the axis thereof, and means associated with said shock-absorbing member for limiting the movement of said circuit interrupter whereby to minimize the bending stress on said insulating support as imposed through said first contact means.

14. An electric circuit interrupting device comprising a cylindrical insulator, a first contact

means mounted on said insulator adjacent one end thereof and extending outwardly from the insulator, a second contact means mounted on the other end of said insulator, an expulsion type circuit interrupter for electrically interconnecting said contact means in a direction forming an acute angle within a range of 10 to 30 degrees with the longitudinal axis of said insulator and spaced therefrom whereby the force exerted during circuit interruption is transmitted to said insulator through relatively short and long lever arms, said short lever arm comprising a support with said circuit interrupter mounted thereon and having a portion spaced from said other end of said insulator and in line with the longitudinal axis thereof, means mounted between said axially aligned portion of said support and said other end of said insulator for absorbing said force and transmitting it to said insulator substantially in line with the longitudinal axis thereof, and means associated with said force absorbing means for limiting the portion of said force exerted on said first contact means.
